UNITED STATES PATENT OFFICE.

HAROLD B. MOWRY, OF STERLING, CONNECTICUT, ASSIGNOR TO THE UNITED STATES FINISHING COMPANY, OF NEW YORK, N. Y., A CORPORATION OF CONNECTICUT.

METHOD AND MECHANISM FOR MARKING MATERIALS.

Application filed April 18, 1923. Serial No. 632,815.

The present invention relates generally to devices or mechanisms for marking and is more specifically directed to improvements in such mechanisms, which are especially designed for applying trade-marks, trade-names and other identifying media to piece or sheet material, such as paper, fabrics and the like.

As is well known, it is a common practice for manufacturers of wall papers, fabrics and the like to apply to the goods of their production trade-marks, trade-names or other insignia to indicate quality, yardage and the like. Such identifying media are usually applied to the selvage of the material by means of decalcomania transfers and various forms of imprints, as well as by embossing.

The mechanisms for applying the aforesaid media on the material are more or less complicated in construction and operation, and generally take the form of a unit which is independent of other mechanisms or machines used in the production of the material, so that to a large extent the application of the manufacturer's trade-mark, trade-name, or the like calls for a separate operation which adds to the cost of production of the material. For example, assuming that it is the practice of the manufacturer to apply his particular marking to fabrics in the piece, after they have been finished, the material, following the finishing operation, must be wound upon a suitable frame or support for the marking operation, following which it is again wound on a carrier from which it is transferred to the bolt boards or the like. Obviously, the several rewinding operations and transportation of the material to the marking mechanism materially increases the operations necessary to obtain the marketable product with a consequent added cost to the manufacturer and consumer.

The general object of the present invention is to eliminate the additional cost of marking the material, which results from the methods now employed, and so simplify the mechanism and method of marking the material that the marking may be accomplished simultaneously with, or as a part of, an essential operation or step in the production of the material. Manifestly, the cost of marking will therefore be a negligible item in the production of the material

for the market, and at the same time the capacity of a given production unit will be increased.

More specifically, it is the object of my invention to provide a simple mechanism for applying any desired markings to paper, fabrics and similar material, which is automatic in operation and may be employed in conjunction with any machine used in the production of the material, where the stage of production may permit of the use of the marking mechanism.

My invention also comprehends a method and mechanism for applying markings to material in which the marking operation is performed by a production unit, as by a calendering machine or other apparatus used in the production or finishing of the material, the marking operation and means for controlling or regulating the same being governed by the material itself, so that the marking of the material is in synchronism with the manufacturing operation being performed thereon.

In marking mechanisms, as heretofore known, it has been customary to employ heat as an agent for effecting the marking, either by decalcomania transfer or otherwise, and in my present invention, I have devised a method and mechanism in which the heat generated in or radiated by the machine, such as a calender, in which the production operation is taking place is utilized to that end, thereby further overcoming the objections to the marking mechanisms as now constituted. This feature of the present invention, however, is described and more particularly claimed in my co-pending application, Serial No. 104,108, filed April 23, 1926.

Other objects and advantages flowing from my invention will present themselves as the description proceeds, and I would have it understood that I reserve unto myself all rights to the full range of equivalents, both in structure and uses, to which I may be entitled under my present invention in its broadest aspect.

For the purposes of the present disclosure, I have elected to illustrate and describe one form of mechanism, whereby my method may be carried out. It will be obvious, however, that the mechanism for practising my method of marking may take other forms to meet special requirements of use

without departing from the spirit and scope of my invention, as defined by the appended claims.

In the drawings:

5 Fig. 1 is an elevation, partly in section, of a preferred form of mechanism as used in conjunction with a unit of a manufacturing equipment, whereby my method may be practised or carried out;

10 Fig. 2 is a top plan view of the structure shown in the left hand half of Fig. 1;

Fig. 3 is a view similar to Fig. 2 of the structure shown in the right hand half of Fig. 1; and

15 Fig. 4 is a plan view section of paper, fabric or the like, the salvage of which has been marked by practising my improved method.

Referring now to drawings in detail, in which like characters of reference are employed to designate similar parts throughout the several views, 7 indicates a reel or spool upon which is wound a relatively narrow ribbon or tape 8 of paper, fabric or other suitable material having equi-distantly spaced laterally extending tabs or projections 9 along one edge thereof. These tabs or projecting portions may be perforated in any suitable manner, as shown at 10, to form a stencil of any desired trademark, or other insignia which is to be affixed to the material to be marked. If desired, in lieu of the aforesaid stencil, said tabs or projections 9 may carry decalcomania transfers or may be otherwise formed to provide a die or other medium for carrying out the objects of this invention in the manner hereinafter described.

40 The reel or spool 7 may be of any diameter to carry the requisite supply of tape or ribbon for any given operation, or for a number of operations as the case may be. This reel or spool 7 is supported or mounted on a stub shaft 11, keyed or splined thereto so as to rotate therewith, the ends of said shaft protruding beyond the plane of the sides of said reel. The said shaft 11 is removably journaled in split bearings supported from the opposite walls 12 and 12^a, respectively, of the protective cage or housing 13 which is preferably formed of sheet metal or any other material suitable to the purpose, and of the configuration shown. The split bearing aforesaid comprises a 45 fixed lower half 14, having extensions 15 and 16, to the former of which the upper half of the bearing 17 is hinged or pivotally connected, as shown at 18.

60 From this construction, it will be observed that the shaft 11 carrying the reel 7 may be positioned within or removed from the bearings with facility and despatch, the shaft being locked in functioning position in the bearings by means of the wing nuts 65 18' in threaded engagement with the studs

19 which are pivotally connected to the extension 16 of the bracket 14, as shown at 20, for entering the open end elongated slots 21 in the extension 22 of the upper half bearing 17.

70 The ribbon or tape 8, which carries the stencil or other medium, by which the material to be operated upon may be marked, as it is unwound from the reel or spool 7, traverses an elongated trough or chute-like guideway 23, which is a continuation of the base and sides of the housing 13, the tape or ribbon 8 as it leaves the spool, passing beneath the roll 24 journaled in the upwardly directed parallel flanges 25, which 75 form the sides of said guideway 23.

80 In the present showing of my invention, I have elected to illustrate the same as used in connection with a calendering machine, such as is commonly employed in finishing fabric and other materials, the calender rolls, the upper one of which is usually a heat roll being indicated by the reference numerals 26 and 27, respectively. The housing 13 with its extending guideway 23 for the tape or ribbon 8 is located in front of, or in advance of the machine rolls 26 and 27. The housing 13 with its extending guideway 23 is pivotally mounted on a bracket 28, slidably mounted on a rod 29, positioned transversely of the calendering machine, the said rod or bar 29 being connected to the calendering machine frame members 30 for adjustment longitudinally thereof. The bracket 28 may be a casting, or may be formed of any suitable material, and is preferably provided with a bore 85 conforming to the contour of the rod or bar 29, and of dimensions to permit of the movement of said bracket longitudinally of said rod or bar, or in other words, transversely of the calendering machine frame, the said bracket being locked in position of adjustment by means of the set screw 31. The aforesaid pivotal connection between the bracket 28 and the housing 13 is obtained by forming an annular pin or protuberance 32 on the upper surface of the bracket 28, which is adapted to enter a complementary recess 33 in the boss or block 34, fixed to the base of the housing 13 by means of rivets or the like 35. By this method of connection between bracket 28 and the boss or block 34, it will be observed that the housing 13, with its extending guideway 23, will be capable of oscillatory movement with relation to the bracket 28, as hereinafter explained.

110 The material 36 to be operated upon by the calender rolls 26 and 27, respectively, traverses the usual guide or tension rolls 37, 38 and 39 and passes between said calender rolls 26 and 27, being carried over a rod or bar 40, positioned transversely of the machine frame and between the roll 39 and 115

calender rolls 26 and 27. This rod or bar 40 forms a table, the top of which is in the plane of the periphery of the adjacent guide or tension roll 39, so that that portion of the material 36 which is supported by said roll 39 and the table 40 is in a substantially horizontal plane.

It will be observed that the terminus of the guideway 23, when the housing 13 is mounted relative to the rolls 26 and 27, as just described, is at a point approximately between the roll 39 and the table 40. Positioned on the outside of the guideway 23, adjacent to its terminus and on the median line thereof, is a dependent lug or stop 41 which is adapted to contact with, or bear against the edge of the material 36 as it passes from the roll 39 to the table 40.

When it is desired to employ my improved method and mechanism for marking the material, the bracket 28 is adjusted laterally of the rod or bar 29, so that the stop 41 will contact with the edge of the material 36 between the roll 39 and the table 40, whereby the selvage of the material 39 will register, or be in line with the tabs or projections 9 of the tape 8. The tape 8 as it leaves the table 40 is in close contact with the material 36 and enters between the calendering rolls 26 and 27 therewith.

The tape 8, as it is unwound from the spool or reel 7 passes under the roll 24, as aforesaid, and is guided in its movement through the guideway 23 by means of fingers 42, which are supported by transverse rods 43^a connected to the edges of the guideway 23. These fingers 42 project downwardly into the guideway and contact with the edge of the tape or ribbon 8, from which the tabs 9 project. The tape 8 in traversing the guideway 23 is thus at all times, during the feeding operation, maintained in position to insure registration of the tabs or projections 9 thereof with the selvage edge of the fabric 36, the pressure of the turned-up end portions 42^a of the fingers 42, in a downward direction, being so adjusted as to permit the tabs or projections 9 of the tape 8 to ride beneath said fingers without injury thereto.

As the material 36 is drawn beneath the calendering rolls 26 and 27, the vibration of the machine and the slight lateral variations in the path of movement of the material are provided for by the aforesaid pivotal connection between the boss or block 34 of the bracket 28. This pivotal connection permits the spring 43 fixed to the bracket as at 44 to exert sufficient lateral pressure against the pin 45 dependent from the underside of the guideway 23 to maintain the lug or stop 41 continuously in contact with the adjacent edge of the material 36.

It will be noted that a portion of the guideway, adjacent to its terminus, overlies

the material 36 in its passage from the roll 39 to the table 40. To prevent undue pressure of such portion of the guideway 23 on the material 36, by reason of the weight of the parts supported by the boss or block 34, I provide a counter-balancing weight 46 threaded on a screw 47 extending from the rear of the housing 13. By this means the position of the guideway, with relation to the material 36, may be accurately maintained during the entire period of the marking operation.

As the tape 8 is drawn beneath the calendering rolls 26 and 27, the tabs or projections 9 of said tape being in contact with the edge of the selvage of the material 36, it will be obvious that the heat of the roll 26 combined with the pressure exerted by said calender rolls on the said tabs and the material will effect a transfer of the indicia, or other marking provided on the tab or projection 9 of the tape 8 to the material. For example, if the tab or projection 9 of the tape 8 is formed to function as a stencil, the heat and pressure of the calender rolls 26 and 27 will produce an impression of the tab or projection 9 upon the selvage of the material, in which the insignia or other markings on the tab appear in relief. On the other hand, if the marking is to take the form of a decalcomania transfer, it will be obvious that the transfer may be made to the material 36 in an equally efficient manner.

In order that the movement of the ribbon or tape 8, through the guideway 23, may be performed so as to synchronize with the speed of the material 36, in its passage between the calender rolls 26 and 27, I provide a brake or governor for the roll or spool 7, which consists of a weight 48 suspended from a strap or other flexible medium 49 detachably connected at its other end to a pin 50 projecting from one side of the housing 13. This strap or flexible medium 49 passes over a grooved pulley 51, which is keyed to one end of the stub shaft 11, as shown at 52, the weight 48 being of the proper size to retard the rotation of the shaft 11 sufficiently to insure the aforesaid synchronization in movement of the tape 8 and the material 36, without producing such an excessive strain on said tape as to cause injury thereto.

I claim:

1. A device of the character described comprising in combination, a support for a roll of tape-like material, said support having a delivery end through which the tape-like material may be withdrawn and mountings for the support whereby the support and delivery end thereof may be laterally shifted and the delivery end elevated or depressed.

2. A device of the character described

adapted for use with strip material handling mechanism, such as calendar rolls, comprising in combination, a support for a roll of tape-like material, said support having a delivery end through which the tape-like material may be withdrawn, and a device for maintaining a predetermined lateral thrust of the support against said strip material.

3. A device of the character described
10 adapted for use with strip material handling mechanism, such as calendar rolls, comprising in combination a support for a roll of tape-like material, said support having a delivery end through which the tape-like material may be withdrawn, and means for maintaining a predetermined downward pressure of the delivery end against said strip material.

4. A device of the character described
20 adapted for use with strip material handling mechanism, such as calendar rolls, comprising in combination, a support for a roll of tape-like material, said support having a delivery end through which the tape-like material may be withdrawn, a device for maintaining a predetermined lateral thrust of the support against an external element, and means for maintaining a predetermined downward pressure of the delivery end against said strip material.

5. A device of the character described comprising in combination, a support for a roll of tape-like material, said support having a delivery end through which the tape-like material may be withdrawn, mountings for the support whereby the support and delivery end thereof may be laterally shifted and the delivery end elevated or depressed, and a friction drag associated with the support for impeding the unwinding of the roll.

40 6. A device of the character described comprising in combination, a support for a

roll of tape-like material, said support having upwardly opening bearings and a horizontal outstanding delivery chute for material drawn from the lower side of the roll, fingers for keeping the material in the chute, and a friction drag to retard the unrolling of the material.

7. A device of the character described 50 comprising in combination, a support for a roll of tape-like material, said support having upwardly opening bearings and a horizontal outstanding delivery chute for material drawn from the lower side of the roll, 55 a mounting for the support whereby the delivery end of the support may be elevated or depressed, and a counterweight for the chute.

8. A device of the character described 60 comprising in combination a support for a roll of tape-like material, said support having upwardly opening bearings and a horizontal outstanding delivery chute for material drawn from the lower side of the roll, 65 a mounting for the support whereby the same may swing on a vertical axis, and a spring operating upon the chute to bias it to a predetermined lateral position.

9. A device of the character described 70 comprising in combination, a support for a roll of tape-like material, said support having upwardly opening bearings and a horizontal outstanding delivery chute for material drawn from the lower side of the roll, 75 a mounting for the support whereby the same may swing on a vertical axis, a spring operating upon the chute to bias it to a predetermined lateral position, fingers for keeping the material in the chute, and a friction drag to retard the unrolling of the material.

HAROLD B. MOWRY.
